UNITED STATES PATENT OFFICE.

OVID B. LAW, OF TOLEDO, OHIO.

TOY.

SPECIFICATION forming part of Letters Patent No. 459,868, dated September 22, 1891.

Application filed November 28, 1890. Serial No. 372,894. (No model.)

To all whom it may concern:

Be it known that I, OVID B. LAW, of Toledo, county of Lucas, and State of Ohio, have invented certain new and useful Improvements 5 in Toys; and I do hereby declare that the following is a full, clear, and exact description thereof, which will enable others skilled in the art to which it appertains to make and use the same, reference being had to the accompanying drawings, and to the letters of reference marked thereon, which form part of this specification.

My invention relates to toys, having especial reference to a toy comprising a hollow transparent vessel containing a clear liquid, 15 a figure representing an animate creature rigidly fixed therein, and a movable object of slightly greater specific gravity than the liquid, the lower portion of the movable object 20 being heavier than the upper portion, the design of the toy being, by the agitation of the liquid, to place the movable object in an upright position upon a particular part of the fixed figure.

25 The invention will first be described in connection with the accompanying drawings, and then be pointed out in the claim.

In the drawings, Figure 1 is a side elevation of a toy constructed in accordance with 30 my invention. Fig. 2 is a longitudinal sectional view of the same.

Referring to the drawings, 1 designates a transparent vessel, preferably globular in form and having a depending handle portion 35 2, adapted to be grasped by the hand of the operator when manipulating the vessel. The depending portion 2 is hollow, as shown at 3, and is adapted to receive a closure 4, which may be an ordinary wooden plug surrounded 40 by a compressible packing 5, made of rubber or any material that will compress sufficiently to render the closure water-tight, or I may employ a cork simply, or any means for closing the opening 3.

45 5' designates an object permanently fixed to the closure. In the present instance I have shown the fixed object as representing a human figure permanently attached at the feet to a tack 6, which is driven into the closure 50 4, thereby firmly securing the figure in position.

7 designates the movable object, which is of slightly greater specific gravity than the liquid and whose lower portion is heavier than its upper portion. I prefer to make the 55 movable object of any suitable impervious material and insert a cork 8 in the upper portion, so as to give buoyancy thereto and cause the movable object to assume normally a vertical position.

60 From the foregoing description the operation will be apparent. The operator grasps the depending portion of the receptacle, and by tilting, capsizing, or gently shaking the vessel, so as to agitate the fluid contained 65 therein, the hat will be caused to rise and float either laterally, vertically, or in the direction necessary to bring it over and upon the head of the figure, the care and perseverance requisite to produce this result, owing 70 to the tendency of the hat to float away from a desired point, causing great amusement to the operator and the spectators.

75 It will be apparent that I may vary the form of the receptacle or the handle and also the character of the fixed and the movable objects without departing from the spirit of my invention.

Having thus fully described my invention, 80 what I claim as new, and desire to secure by Letters Patent, is—

In a toy, the combination, with a transparent vessel containing a clear liquid, of a figure representing an animate creature rigidly fixed within the vessel, and a movable object within 85 the vessel, the movable object being of slightly greater specific gravity than the liquid and heavier in its lower portion than in its upper portion, whereby by agitating the liquid the movable object may be placed in an upright 90 position upon a particular part of the fixed figure.

95 In testimony that I claim the foregoing as my own I affix my signature in presence of two witnesses.

OVID B. LAW.
